US00D852077S

(12) **United States Design Patent** (10) **Patent No.:** **US D852,077 S**
(45) **Date of Patent:** **** Jun. 25, 2019**

(54) **CHIME**

(71) Applicant: **SkyBell Technologies, Inc.**, Irvine, CA
(US)

(72) Inventors: **Dashawn Davon Seaberry**, Irvine, CA
(US); **Seton Paul Kasmir**, San Diego,
CA (US); **Joseph Frank Scalisi**, Yorba
Linda, CA (US); **Desiree Mejia**, Yorba
Linda, CA (US)

(73) Assignee: **SkyBell Technologies, Inc.**, Irvine, CA
(US)

(**) Term: **15 Years**

(21) Appl. No.: **29/635,841**

(22) Filed: **Feb. 2, 2018**

(51) LOC (11) Cl. **10-05**

(52) U.S. Cl.

USPC **D10/118**

(58) **Field of Classification Search**

CLAIM

The ornamental design for a chime, as shown and described.

DESCRIPTION

FIG. 1 is a front and first side perspective view of a chime embodying the new design;

FIG. 2 is a front and second side perspective view thereof;

FIG. 3 is a front view thereof;

FIG. 4 is a back view thereof;

FIG. 5 is a second side view thereof;

FIG. 6 is a first side view thereof;

FIG. 7 is a top view thereof; and,

FIG. 8 is a bottom view thereof.

The broken lines depict portions of a chime in which the design is embodied and form no part of the claimed design.

1 Claim, 4 Drawing Sheets
